UNITED STATES PATENT OFFICE.

CLARENCE CHRISTIAN SMALLEY, OF MANITOWOC, WISCONSIN.

TREAD-POWER GOVERNOR.

SPECIFICATION forming part of Letters Patent No. 357,239, dated February 8, 1887.

Application filed October 7, 1886. Serial No. 215,554. (No model.)

To all whom it may concern:

Be it known that I, CLARENCE CHRISTIAN SMALLEY, a citizen of the United States, residing at Manitowoc, in the county of Manitowoc and State of Wisconsin, have invented certain new and useful Improvements in Tread-Power Governors; and I do hereby declare that the following is a full, clear, and exact description of the same, reference being had to the annexed drawings, making a part of this specification, and to the letters and figures of reference marked thereon.

Figure 1 of the drawings is a side elevation of my improved governor, showing its application to a tread-power; Fig. 2, an end view thereof, partly in section; Fig. 3, a side elevation of the governor on an enlarged scale, showing the driving-shaft in section; and Fig. 4, a vertical section taken on line *y y* of Fig. 3.

The present invention has relation to certain new and useful improvements in governors for tread-powers, which are connected by belts to any desirable machinery that is to be operated, such as feed-cutters, grinders, corn-shellers, wood-saws, and other like machines. In this class of powers the speed under ordinary circumstances greatly varies, as for instance, in cutting feed or grinding grain, when the box of the cutter or grinder runs out of material to operate upon, and in such case the want of resistance is immediately felt by the horses in the power, and they change at once into a quicker walk, and then into a run, until the operator has either time to put on the brake or supply more material to the cutter or grinder. Such an incident is very common in operating an ordinary tread-power, and is often the occasion of great damage to either the machine or the team, or both.

It is the object of the invention to provide a simple and perfectly-operating governor, whereby the objections above named are removed, which I attain by the construction substantially as shown in the drawings, and hereinafter described and claimed.

In the accompanying drawings, Fig. 1, is shown one of many forms of tread-power to which my invention is applicable, said power consisting of the usual frame, *A*, and the end-less belt composed of transverse parallel bars *a*, held or hinged together by means of toothed

links in the ordinary manner. The teeth of the links, as shown at *b*, engage with the teeth of a pinion, *c*, upon a driving-shaft, *B*, the links at the ends of the bars being connected together by shafts *d*, loosely passing through them, and provided at their extremities with flanged friction-rollers *e*, which run on suitable tracks, *f*, as shown more clearly in Fig. 2, when the belt is forced around by the weight of the horses or other animals walking thereon.

To one end of the driving-shaft *B* is suitably connected a band-wheel, *C*, and from this wheel extends the driving-belt to any desirable machinery that is to be operated.

To the frame *A* is bolted or otherwise suitably attached a circular rim, *D*, which encircles the operating parts of the governor, the driving-shaft forming the center of said rim, the latter having a smooth inner surface, the width of which may vary in size, according as it is to be used for greater or less power.

A bracket, *E*, which forms the main center piece of the governor, is fastened to the driving-shaft *B* by means of a key, set-screw, or otherwise, and is constructed with cored ends, as shown at *g*, to admit the supports *F*, said supports having pivoted to them the wooden blocks *G*. These blocks are held in position by means of spiral or other suitable springs, *h*, and in such a manner that when the machine or power is running at any ordinary or desired speed there will be no friction between the blocks *G* and rim *D*, said springs being coiled around supporting-rods *i*, which pass through holes in lugs *k* upon the support *F*, and their tension may be regulated by means of nuts *l* upon the screw-threaded ends of the rods.

The bracket *E* is provided with two elbows, *m*, near its ends, and extending laterally in opposite directions, for the purpose of holding the regulating-springs *H*, which are coiled around rods *n*, the inner ends of which are suitably connected to the ends of a sway-bar, *I*, projecting from a sleeve, *o*, through which passes the driving-shaft *B*, the sleeve *o* being of sufficient diameter to play loosely thereon.

To the bracket *E*, near its ends, are pivoted the weighted arms *K*, which have eccentrically-shaped ends. These arms, by means of centrifugal force, will be thrown outward, the eccentric ends thereof, as shown at *p*, coming in

contact with the friction-rollers *q* upon the inner ends of the supports *F*, which in turn have the wooden blocks *G* pivoted thereto. As the weighted arms are thrown outward the wooden blocks are forced in contact with the inner periphery of the rim *D*, and sufficient friction is produced to lessen materially the speed of power. Now, to properly regulate this friction, which would otherwise be too great for practical use, the sway-bar *I* is attached to the weighted arms *K*, near their eccentric ends, by means of links *r*, and to the ends of the sway-bar, as hereinbefore described, are connected the rods *n*, around which are coiled the springs *H*. Now, as will be readily seen, the weighted arms *K* must overcome the resistance caused by the springs *H* before they can work outward and communicate friction to the rim *D* by means of the wooden blocks *G*, and, in consequence, when the springs are tightened or their coils compressed by the action of the sway-bar it will require a greater centrifugal force to move the weighted arms from their dormant position, and if a higher speed of power is desirable it is obtained by simply tightening or compressing the coils of the spring by means of the nuts *s* upon the screw-threaded ends of the rods *n*. If, on the contrary, a less speed is desirable, the tension of the springs is loosened in the same manner, the arms moving outward with a less centrifugal force, and the friction thereby will be produced at a slower speed.

The bracket *E* is preferably provided with lugs *t* on its outer side for convenience of attaching or assisting in holding the band-wheel *C* in position on the shaft, and is of great advantage in that it enables the governor to be attached to any ordinary tread-power, while if it did not possess this feature it would necessitate the lengthening of the shaft in order to accommodate both the governor and band-wheel.

Having now fully described my invention, what I claim as new, and desire to secure by Letters Patent, is—

1. In a speed regulator or governor for tread-powers, a stationary circular rim and a bracket attached to the driving-shaft, in combination with friction-blocks and supports therefor, provided with friction-rollers, and pivoted weighted arms having eccentrically-formed ends to bear against said rollers for forcing the friction-block against the inner periphery of the rim, substantially as and for the purpose described.

2. In a speed regulator or governor for tread-powers, the combination, with a stationary circular rim, of a bracket carrying the operating parts of the regulator or governor, and provided upon its outer side with lugs to assist in holding the band-wheel in position on the shaft, said bracket being attached to said shaft and revolving therewith, substantially as and for the purpose described.

3. In a speed regulator or governor for tread-powers, a bracket attached to the driving-shaft and provided at its ends with supports and friction-blocks pivoted thereto, springs and rods, arranged as shown, for controlling the action of the blocks, and friction-rollers connected to the supports, in combination with weighted arms pivoted to the bracket and having eccentrically-formed ends, sway-bars loosely mounted on the driving-shaft and connected to the arms by links, and regulating-springs for controlling the action thereof, substantially as and for the purpose specified.

In testimony that I claim the above I have hereunto subscribed my name in the presence of two witnesses.

CLARENCE CHRISTIAN SMALLEY.
